DESIGN FOR AN URN

Filomeno Palladino, Newark, N. J.

Application March 28, 1935, Serial No. 56,096

Term of patent 7 years

To whom it may concern:

Be it known that I, Filomeno Palladino, a citizen of the United States, residing at Newark, in the county of Essex and State of New Jersey, have invented a new, original, and ornamental Design for an Urn, of which the following is a specification, reference being had to the accompanying drawing, forming part thereof:

showing my new design. Figure 2 is a rear elevational view of the same, showing an opening to the hollow interior and provided with a closure. Figure 3 is a side, back perspective view thereof.

I claim:

The ornamental design of an urn, as shown and described.

FILOMENO PALLADINO.
